(57) **CLAIM**

The ornamental design for a desk organizer as shown and described.

DESCRIPTION

FIG. 1 is a front perspective view of a desk organizer, showing my new design;

FIG. 2 is a top perspective view thereof;

FIG. 3 is another front perspective view of the desk organizer from another angle;

FIG. 4 is a rear perspective view thereof;

FIG. 5 is a front elevational view thereof;

FIG. 6 is a rear elevational view thereof;

FIG. 7 is a left side view thereof;

FIG. 8 is a right side view thereof;

FIG. 9 is a top plan view thereof; and,

FIG. 10 is a bottom plan view thereof.

The dashed broken lines in the figures are for the purposes of illustrating portions of the desk organizer and form no part of the claimed design.
